UNITED STATES PATENT OFFICE

JOHN HUTTER, OF LOS ANGELES, CALIFORNIA, ASSIGNOR TO A. J. BAYER COMPANY, OF LOS ANGELES, CALIFORNIA, A CORPORATION OF CALIFORNIA

DESIGN FOR A GRAVE MARKER

Application filed June 25, 1931. Serial No. 40,325. Term of patent 7 years.

To all whom it may concern:

Be it known that I, JOHN HUTTER, a citizen of the United States, residing at Los Angeles, in the county of Los Angeles and State of California, have invented a new, original, and ornamental Design for a Grave Marker, of which the following is a specification, reference being had to the accompanying drawings, forming a part hereof.

In the drawings, Fig. 1 is a plan view of a grave marker, showing my new design, and Fig. 2 is a side view thereof.

The essential feature of the design is the panel having the landscape thereon framing the name, relationship and data concerning the life span of the deceased.

The matter shown in dotted line is not regarded as a part of the design, but is included to show how such information may be added if desired.

I claim:

The ornamental design for a grave marker, substantially as shown and described.

JOHN HUTTER.
